CLAIM

The ornamental design for a combined connection cabinet and printed circuit board housings, as shown and described.

DESCRIPTION

FIG. 1 is a front and upper right isometric view of a combined connection cabinet and printed circuit board housings showing my new design;

FIG. 2 is a right elevation of the design;

FIG. 3 is a left elevation of the design;

FIG. 4 is a bottom view of the design;

FIG. 5 is a top view of the design;

FIG. 6 is a front view of the design;

FIG. 7 is a rear view of the design;

FIG. 8 is a front and upper right isometric view of a second embodiment of a combined connection cabinet and printed circuit board housings showing my new design. All other views are the same as the first embodiment except for the variation in the arrangement of the circuit board housings; FIG. 9 is a view of the embodiment of FIG. 1 with two additional circuit board housings removed; and, FIG. 10 is a rear and lower left isometric view of the first embodiment.
